SANDWICH SPREADER OR SIMILAR ARTICLE

Richard Hopcraft, Providence, R.I., assignor to Imperial Knife Associated Companies, Inc., New York, N.Y., a corporation of Rhode Island

Original design application Aug. 10, 1967, Ser. No. 8,213, now Patent No. 211,681, dated July 9, 1968. Divided and this application Feb. 8, 1968, Ser. No. 10,503

Term of patent 14 years

U.S. Cl. D44—29
Int. Cl. D7—02

FIG. 1 is a left side elevational view of a sandwich spreader or similar article showing my new design:

FIG. 2 is a front elevational view;

FIG. 3 is a right side elevational view;

FIG. 4 is a rear elevational view; and

FIG. 5 is an elevational view from the bottom of FIG. 1.

The dominant features of the design are shown in full lines.

This is a division of my earlier-filed application Ser. No. D-8,213 of Aug. 10, 1967, now patent D-211,681 of July 9, 1968.

I claim:

The ornamental design for a sandwich spreader or similar article, substantially as shown and described.
